UNITED STATES PATENT OFFICE.

WILLIAM SCHNEIDER, OF CHICAGO, ILLINOIS, ASSIGNOR TO THE WHITFIELD COMPANY, OF NEW YORK, N. Y., A CORPORATION OF MISSISSIPPI.

TELESCOPIC COMPOUND ENGINE.

SPECIFICATION forming part of Letters Patent No. 716,115, dated December 16, 1902.

Application filed October 21, 1901. Serial No. 79,466. (No model.)

To all whom it may concern:

Be it known that I, WILLIAM SCHNEIDER, a citizen of the United States, residing at Chicago, in the county of Cook and State of Illinois, have invented certain new and useful Improvements in Telescopic Compound Engines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 This invention has relation to that type of telescopic compound steam-engines comprising a low-pressure cylinder, a stationary abutment, a high-pressure piston-cylinder working in said low-pressure cylinder and on 20 said abutment, the inner head of said high-pressure cylinder constituting the differential piston for said cylinders, and a valve-casing and valve located axially within the cylinders.

25 In my application for Letters Patent of the United States filed October 2, 1901, Serial No. 77,293, I have referred to the discovery made by me that by closing the usually open outer end of the high-pressure cylinder of an engine of the type referred to and that by a proper arrangement of the steam-ports and the provision of a suitable valve for controlling said ports I am enabled to convert the engine into a triple-expansion engine without increasing or materially increasing its 30 dimensions. In my said application I have also shown a construction of low-pressure cylinder whereby an auxiliary annular exhaust-port of comparatively great cross-sectional area is obtained, for purposes fully described, by interrupting the continuity of said cylinder at a suitable point, but that this auxiliary exhaust-port was not absolutely necessary to the good operation of the engine. I 35 have since discovered that a triple-expansion engine, such as described in my said application, can be converted into a double-acting compound engine or into a quadruple-expansion engine by utilizing the low-pressure-cylinder space on the side of least cross-sec-

tional area of the differential piston of the engine as a fourth cylinder, the auxiliary annular exhaust-port formed by interrupting the continuity of the low-pressure cylinder above referred to being of course dispensed 55 with and the location of the steam-ports altered to suit the altered function of the engine and suitable valves provided for controlling said ports. It will readily be seen that by closing the outer end of the high-pressure cylinder at a suitable point two cylinders or pressure-chambers of different cross-sectional areas are obtained by reason of the displacement of the axially-arranged valve-casing on one side of the stationary abutment, which therefore constitutes the differential piston for said chambers. Furthermore, the cross-sectional area of the fourth chamber—namely, the one on the side of least cross-sectional area of the piston-head of the 70 high-pressure cylinder—is greater than that of the aforementioned chambers, but of less cross-sectional area than that of the low-pressure-cylinder chamber on the side of greatest cross-sectional area of said piston-head of the high-pressure cylinder, which latter, therefore, performs not only the function of differential piston for the low-pressure and the high-pressure chambers, but also for the low-pressure chamber and the second intermediate-pressure chamber.

That my invention may be fully understood I will describe the same in detail, reference being had to the accompanying drawings, in which—

Figure 1 is a fragmentary vertical section, and Fig. 2 a vertical section of a double-acting compound telescopic engine, illustrating my invention, the high-pressure piston-cylinder being shown at the limit of its instroke 90 in Fig. 1 and at the limit of its outstroke in Fig. 2. Figs. 3 and 4 are fragmentary vertical sections of a quadruple-expansion engine, the pistons being shown at the limit of their in and out strokes, respectively. Fig. 95 5 is a section on line X Y of Fig. 1 or of Fig. 3, and Fig. 6 is a fragmentary sectional development of the valve-casing.

Referring to the drawings, *a* indicates the low-pressure cylinder, *e* the high-pressure

cylinder closed at *g* near its outer end and connected in the usual manner with the crank-shaft of the engine through connecting-rod 38.

l indicates the stationary abutment, *h* the 5 axially-arranged combined valve-casing and supplementary steam-chest and supplementary receiver, hereinafter referred to as the "valve-casing," which is preferably, though not necessarily, formed integral with said 10 abutment, which latter is closed at its outer end by a suitable head, said valve-casing being removably secured to the head *k* of the low-pressure cylinder.

The high-pressure cylinder *e* is guided in a 15 tubular extension *d*, formed on a frame *b*, to which the low-pressure cylinder is secured.

From the construction and arrangement as described it will be observed that the stationary abutment *l* divides the high-pressure 20 cylinder into two cylinders or pressure-chambers—namely, a high-pressure chamber 35, and a first intermediate-pressure chamber 36—while the piston *f* of the low-pressure cylinder divides said low-pressure cylinder into 25 two cylinders or pressure-chambers—namely, into a second intermediate-pressure chamber 34 and a low-pressure chamber 37.

By a suitable disposition of the steam-ports and the provision of suitable valves the engine can be operated as a quadruple-expansion engine or as a double-acting compound engine, which latter I will now describe, referring to Figs. 1 and 2, wherein *i* indicates the internal valve, and *y* the external valve, 30 both being tubular, open at both ends, and of reduced diameter between their opposite ends to form the steam-passages 14^a and 15, respectively, between them and their casings, the external valve *y* working in a casing *x*, 35 secured to or formed integral with the low-pressure cylinder, said valve receiving its motion in any usual manner from the crank-shaft through a suitable eccentric thereon, (not shown,) to which eccentric is connected 40 one end of the stem 21 of said valve by means of a connecting-rod *z*. The opposite end of the valve-stem 21 is connected to a radial arm 11 on a rock-shaft 18, which has its bearings in standards bolted to the head *k* of the low-pressure cylinder, said rock-shaft having secured thereto a second radial arm 20, to which is connected the stem *u* of the internal valve *i*. The external-valve casing *x* has an exhaust branch 40, and the head *k* of the low-pressure 50 cylinder is divided by a partition 23, and the valve-casing *h* into a receiver-chamber *p* and a live-steam chamber *q*, having ports 25^a and 1, respectively, in communication with the receiver-space 4 and the live-steam space 2 in 55 said valve-casing *h*, said live-steam chamber *q* being in communication through a passage *r* with the steam-inlet port *s*. The internal-valve casing is provided with the long port 7 and with suitably-located ports 25 and passages 26. In the stationary abutment *l* are 60 formed steam-passages 5, and at its opposite ends the low-pressure-cylinder has passages

6 and 28 in communication with the external-valve casing *x*. The operation of the engine is as follows: Supposing the high-pressure 70 piston-cylinder to be at or about at the limit of its outstroke and the internal and external valves *i* and *y* at or about at the limit of their instroke, Fig. 2, steam flowing from steam-chest *q* 2, ports 25, passages 14^a and 26 into 75 high-pressure-cylinder space 35, causing the high-pressure piston-cylinder to make its instroke. At the completion of said instroke the valves *i* and *y* will be at the limit of their outstroke, Fig. 1, live steam then flowing from 80 *q* 2, 25, 14^a, and 5 to intermediate-pressure chamber 36, causing the high-pressure piston-cylinder *e* to make its outstroke. At the same time, however, steam from high-pressure chamber 35 exhausts through passage 26, 85 valve-casing *h*, and ports 7 into receiver 4 *p*, while the low-pressure-cylinder space 37 is in communication with the exhaust branch 40 through ports 6 and passage 15 between valve *y* and its casing *x*. At the completion of said 90 outstroke, Fig. 1, the steam from intermediate-cylinder space 36 is exhausted into the receiver 4 *p* through passages 5, valve *i*, valve-casing *h*, and its port 7, live steam being admitted to the high-pressure cylinder *e*, as 95 above set forth, while steam from said receiver is admitted through valve-casing *x*, valve *y*, and passage 28 into the second intermediate-pressure chamber 34, the high-pressure cylinder *e* making its instroke under the 100 action of live steam and the expansion of the first intermediate-pressure steam. At the completion of this second instroke, Fig. 2, live steam is admitted to the first intermediate-pressure chamber 36, as before, steam is 105 exhausted from the second intermediate-pressure chamber 34 into the atmosphere through passage 28, external-valve passage 15, and exhaust-port 40, while steam from receiver *p* is admitted to low-pressure chamber 37 through 110 passage 6, the outstroke of the high-pressure piston-cylinder *e* being effected under the action of live steam and under expansion of low-pressure steam. Finally at the completion of this last outstroke live steam will be 115 admitted to the high-pressure chamber 35, intermediate-pressure steam from first intermediate-pressure chamber 36 exhausting into receiver 4 *p*, while intermediate-pressure steam from receiver will be admitted to second intermediate-pressure space 34 and low-pressure steam exhausting from low-pressure chamber 37 into the atmosphere through passage 6, external-valve-casing passage 15, and port *s*, the engine being now in working order, the instroke being effected under the action of live steam and expansion of first intermediate-pressure steam, while the outstroke is effected by live steam in first intermediate-pressure chamber 36 and by expansion of low-pressure steam in low-pressure chamber 37, 120 and so on.

Referring now to Figs. 3 and 4, which illustrate the quadruple-expansion engine, it will

be seen that there is no change in the general construction of the engine, and by the mere substitution of a suitable internal-valve casing and valve and a suitable external valve a double-acting compound engine can be converted into a quadruple-expansion engine. The valve-casing *h* has at its lower end an annular steam-passage 27, leading from the high-pressure chamber 35 into the valve-casing, and above said annular passage 27 the casing has a port or ports 29, leading from the live-steam space 2 into said valve-casing. The internal valve *i* is of substantially the same construction as that shown in Figs. 1 and 2, except that its upper valve-face 30 is made longer. The external valve *y* is likewise of substantially the same construction as that shown in Figs. 1 and 2, with this exception—it is much shorter and has its upper or inner valve-face 31 also made longer and provided with a port 32, adapted to place the valve and its casing in communication with the low-pressure chamber 37. Finally the external-valve casing has a passage 33, which places it in communication with the receiver-space *p* through the ports 39, and said casing has its exhaust-port 40 at the inner end thereof. The valve-rods may be connected as shown in Figs. 1 and 2, or they may be connected to the differential arms of a rock-lever 41 on rock-shaft 18, as shown. The operation will be as follows, the high-pressure piston cylinder and valves being in the position shown in Fig. 4: Live steam from *q* 2 is admitted to high-pressure chamber 35 through ports 29, passage 14^a, annular passage 27, and its ports leading to and from the valve-casing to said high-pressure chamber, the high-pressure piston-cylinder making its *instroke*. At the completion of this *instroke*, Fig. 3, steam from the high-pressure chamber 35 will exhaust into the first intermediate-pressure chamber 36 through passages 27, 14^a, and 5, the high-pressure piston-cylinder making its *outstroke* by expansion of steam from the high-pressure chamber. At the completion of said *outstroke*, Fig. 4, live steam will again be admitted to the high-pressure chamber 35, as above set forth, while the steam in first intermediate-pressure chamber 36 will exhaust into receiver *4 p* through passages 5, valve *i*, and port 7, which steam will flow from receiver to second intermediate-pressure chamber 34 through passage 33, ports 39, and passage 28, the high-pressure piston-cylinder making its second *instroke* under live-steam pressure and expansion of first intermediate steam-pressure. At the completion of this second *instroke*, Fig. 3, steam from second intermediate-pressure chamber 34 will exhaust into the low-pressure chamber 37 through passage 28, external-valve casing *x*, its valve *y*, valve-port 32, and passage 6, while steam from the high-pressure chamber 35 will exhaust into the first intermediate-pressure chamber 36, the high-pressure piston-cylinder making its second *outstroke* un-

der the expansion of first intermediate and low pressure steam. At the completion of this second *outstroke*, Fig. 4, live steam will be admitted to the high-pressure chamber 35, steam from the first intermediate-pressure chamber will exhaust into the receiver, steam from the latter will be supplied to the second intermediate-pressure chamber 34, while steam from the low-pressure chamber 37 will exhaust into the atmosphere through passage 6, valve-casing *x*, and exhaust-port 40. The engine being now in working order the *instroke* will be effected by live steam in high-pressure chamber 35 and by expansion of steam in first intermediate-pressure chamber 34, steam from low-pressure chamber 37 exhausting through port 40, while the *outstroke* will be effected by expansion of steam from high-pressure chamber 35 in first intermediate-pressure chamber 36 and by expansion of steam from second intermediate-pressure chamber 34 and low-pressure chamber 37, and so on. It will be observed that the internal-valve casing *h* is closed at both ends and forms therefore a part of the receiver *4 p*, the parts being practically steam-jacketed, so that loss of power by condensation is reduced to a minimum.

In engines constructed for operation as described it is difficult to exhaust water of condensation from the high-pressure chamber 35 and the first intermediate-pressure chamber 36 of a double-acting compound or quadruple-expansion engine organized as described. This difficulty I avoid, as shown in the double-acting compound engine by the provision of blow-off pipes *P*² *P*³, the former extending through the receiver-space 4 and steam-passage 26 into proximity to the stationary abutment, while pipe *P*³ extends through the live-steam space 2 and one of the passages 5, leading to the first intermediate-pressure chamber 36, so that the outer end of said pipe will lie in close proximity to the head *g* of said pressure-chamber at the completion of the *instroke* of the high-pressure piston-cylinder, the inner end of pipe *P*² communicating with the exhaust-chamber and the like end of the pipe *P*³ with the receiver-space. Substantially the same arrangement prevails in the quadruple-expansion engine, the pipe *P*², which drains the high-pressure-cylinder space, extending through one of the receiver-spaces 4 and the passage 27 into close proximity to the inner face of the stationary abutment *l*, while the pipe *P*³ extends through the live-steam chamber 2, the aforesaid steam-passage 27, and one of the passages 5 in said abutment.

Having thus described my invention, what I claim as new therein, and desire to secure by Letters Patent, is—

1. A telescopic engine, comprising an outer stationary cylinder, an inner closed and movable piston-cylinder, an axially-disposed valve-casing and a stationary abutment at one end thereof, said parts constructed and arranged to divide the movable and station-

ary cylinder each into two pressure-chambers of unequal cross-sectional areas and means whereby the four-cylinder engine thus obtained can be operated either as a double-acting compound or as a quadruple-expansion engine, substantially as set forth.

2. A telescopic engine, comprising an outer stationary cylinder, an inner, movable piston-cylinder, an axially-disposed valve-casing and a stationary abutment at one end thereof, said parts being so arranged as to divide both the inner and the outer cylinders each into two pressure-chambers of unequal cross-sectional areas; in combination with a suitable valve in said valve-casing, an auxiliary valve operating with the first-named valve, and suitably-disposed steam ports and passages controlled by said valves, whereby the engine may be caused to operate as a double-acting compound engine or as a quadruple-expansion engine, substantially as set forth.

3. A telescopic engine, comprising an outer stationary cylinder, an inner movable piston-cylinder, an axially-disposed valve-casing and a stationary abutment at one end thereof, said stationary abutment dividing the inner cylinder-space into two pressure-chambers of unequal cross-sectional areas by reason of the displacement of the valve-casing on one side of said abutment, the piston-head of the movable piston-cylinder dividing the stationary cylinder into two pressure-chambers of unequal cross-sectional areas and of greater cross-sectional areas than the pressure-chambers of the inner cylinder; in combination with means for causing the four-cylinder engine to work as a double-acting compound engine or as a quadruple-expansion engine, for the purpose set forth.

4. A telescopic engine, comprising an outer stationary cylinder, an inner movable piston-cylinder, an axially-disposed valve-casing and a stationary abutment at one end thereof, said stationary abutment dividing the inner cylinder-space into two pressure-chambers of unequal cross-sectional areas by reason of the displacement of the valve-casing on one side of said abutment, the piston-head of

the movable piston-cylinder dividing the stationary cylinder into two pressure-chambers of unequal cross-sectional areas and of greater cross-sectional areas than the pressure-chambers of the inner cylinder; in combination with an internal valve in said valve-casing, an external valve connected with and operating said internal valve, and suitably-disposed steam ports and passages controlled by said valves, whereby the engine can be operated as a double-acting compound or as a quadruple-expansion engine, substantially as set forth.

5. Means for converting a telescopic compound engine comprising a low-pressure cylinder, a stationary abutment, an open-ended high-pressure cylinder working in said low-pressure cylinder and on said abutment, and an axially-disposed valve-casing carrying said abutment, into a quadruple-cylinder engine, which means consists in a head closing the open end of the high-pressure cylinder at a suitable point, in a suitable arrangement of steam-ports, and in combination therewith of a valve mechanism controlling said ports, and whereby all four cylinders are utilized as working cylinders, for the purpose set forth.

6. In a telescopic steam-engine such as described, the combination with the low-pressure cylinder, the stationary abutment and the high-pressure piston-cylinder closed at its outer end; of means for draining the high and intermediate pressure chambers, comprising two drain-pipes arranged between the concentric walls of the valve-casing and extending from the high-pressure chamber and the intermediate-pressure chamber respectively into the exhaust and receiver spaces in the head of said low-pressure cylinder, substantially as set forth.

In testimony that I claim the foregoing as my invention I have signed my name in presence of two subscribing witnesses.

WILLIAM SCHNEIDER.
